UNITED STATES PATENT OFFICE.

FRANK H. LEFROY, OF NEW YORK, N. Y.

CHANGEABLE GEARING.

SPECIFICATION forming part of Letters Patent No. 556,852, dated March 24, 1896.

Application filed July 2, 1895. Serial No. 554,746. (No model.)

To all whom it may concern:

Be it known that I, FRANK H. LEFROY, a citizen of the United States, residing at New York, in the county of New York and State 5 of New York, have invented certain new and useful Improvements in Changeable Gearing; and I do hereby declare the following to be a full, clear, and exact description of the invention, such as will enable others skilled in 10 the art to which it appertains to make and use the same.

This invention relates to an improvement in gearing for crank-actuated vehicles, and it is embodied in the construction and arrangement of members hereinafter referred to and 15 definitely pointed out in the claims.

The invention is designed more particularly for application to bicycles and tricycles, and is applicable to either the crank-shaft or the 20 shaft of the driving-wheel.

Primarily the invention is designed to afford a very positive and easy variation of the leverage and consequently the speed of the driving-chain or other power-transmitting in- 25 strumentality.

While I have suggested that the invention is applicable to certain classes of vehicles, I 30 wish it understood that it may be applied to other classes of machinery with equally as good results.

Heretofore it has been suggested to vary the speed of the driving means or chain by shifting multiple gear of varying diameter, the gears being internal gears, and conse- 35 quently limiting the number of variations to the interior diameter of the smallest gear, and in such constructions the multiple gears are of necessity loosely mounted eccentrically, and are susceptible of disarrangement by the 40 warping or bending of their supports, thereby throwing their teeth out of true alignment with the moving pinion. These, as well as other objections, can be urged against structures employing internal multiple gears. It 45 has also been suggested in numerous cases to employ a shifting-gear, which may be em- 50 ployed eccentrically as well as concentrically, but which provides for but one change of speed. Such devices are, however, unsatisfactory, owing to the limit of variation and to the general complicated arrangement of

parts. With my invention these objections are practically overcome.

In the drawings, wherein the preferred form of the invention is illustrated, and in which like letters of reference designate corresponding parts in the several views, Figure 1 is a longitudinal vertical section taken through the crank-shaft and sleeve of a bicycle. Fig. 2 is an elevation looking to the left hand of Fig. 1 and showing the shaft in section. Fig. 3 is a detail perspective of the shifting device.

In the drawings, A designates the crank-shaft, B the sleeve, and C the crank, all of usual construction, with the exception that the shaft A has a longitudinal spline b thereon between the end of the sleeve and crank. 65

Slidably supported on the shaft is the multi-gear D, the same being prevented from independent rotation by having a groove cut 70 in its inner wall into which the spline b passes. This gear D is composed of a stepped series of disks d d' d'', each having a diameter differing from the other, arranged side by side and each being formed with external teeth, 75 as shown. These gears constitute by preference an integral unit, but it is to be understood that they can be otherwise formed or constructed—as, for instance, the several steps of the gear can be made separately and 80 then bolted together. The inner wall of gear D is recessed and a circumferential groove d' is formed in the edge wall of this recess, for purposes presently to be explained.

E designates the sprocket-wheel, which is 85 in the form of a ring having the sprocket-teeth on its outer periphery and a series of gear-teeth on its inner peripheral wall. The diameter of the interior of the ring is substantially equal to the diameter of the part d of 90 the gear, so that the latter will closely fit within the former, the teeth of the respective members intermeshing.

To independently support the sprocket-ring I form a groove in its inner side face and secure therein by a suitable locking-ring F the carrying-frame G, consisting preferably of a ring having a flange fitting in the recess. Suitable balls may be interposed, if desired, to form an antifriction-bearing for the sprocket-ring on the frame. The carrying-frame is 100 fixedly held from rotation by being supported

on suitable arms g g' projecting outward from a sliding frame H and connected with the carrying-frame G at its bottom and sides only, so that the upward movement of the ring is unopposed by the arms.

The sliding frame H comprises the two curved side bars h h' curved on a radii with its center the center of the rear axle to prevent the binding of the chain by the adjustments. These side bars are connected at their tops and bottoms by the web h^2 and the cross-bar h^3 .

K designates the supporting-plate keyed or otherwise fixedly secured on the end of the sleeve B . This plate is fashioned to conform to the shape of the frame H , but is somewhat smaller, its side edges being fitted in grooves h^4 formed in a flange h^5 on the side bars only of the frame H . By this means it will be apparent that the frame H will have or be permitted a substantially vertical movement on the supporting-plate or at about right angles to the shaft, and by its movement the sprocket-ring will be raised or lowered, as the case may be.

The flanges h^5 on the bars h h' project laterally beyond the cross-bar and web, so that the frame H is permitted a movement which will carry its opposite ends beyond the plate K , the limit of movement being governed by the distance between the cross-bar and web, which, as will be readily understood, can be greatly varied without necessitating structural changes in the machine-frame.

To effect the relative adjustment of the sprocket ring and gear I employ what I term an "adjuster" or cam L , which consists of a flat plate l having a circular aperture therein, and sleeve the same loosely on the hub k of the fixed plate K , the same being properly held in place by a suitable nut. The plate l has an arm or actuating-lever L' thereon, which extends upward to any convenient point and by which the same may be shifted or rotated about its axis. In the lower and side portions of the plate l is formed a cam-path l' fashioned to correspond to the required vertical movement of the sprocket-ring. Into this cam path or groove l' is extended a pin m made fast to the web h of the plate H , so that as the plate l is rotated the plate H will be raised or lowered through the medium of the pin, the pin working in a slot k^3 in the plate K .

To provide for the movement of the gear D , I form a squared hollow bushing k' on the plate K , and through this bushing pass a link M squared in cross-section and having a hook o at its outer end which loosely engages in the groove d^3 of the gear D . The opposite end of the link is turned down or hooked, as at o' , and passes into a cam-groove l^2 formed in a circular-shaped flange concentrically mounted or formed on the side of the plate l of the adjuster L .

By reference to the drawings it will be noted

that the cams l' l^2 are so arranged that while one serves to elevate the pin therein the other, being horizontal, will serve to move the link at right angles to the other. These cam-grooves are so shaped that the movement of the parts will be properly timed, and when needed the movement of the gear will be stopped and both movements interrupted or locked by interrupted pitches in the cams.

It will be noted that the shifting device and the supporting-frame H are both arranged inwardly beyond the gear and are therefore located in a position to prevent accidental interference, and at the same time may be readily applied to the usual structure without materially altering the parts.

In operation, by shifting the lever L' the gear is moved longitudinally, and as its succeeding step reaches the plane of the sprocket-ring the latter is lowered onto the gear and the speed thereby varied, the movement being simple and effective. By forming the bushing on the plate K the link M is held in its horizontal position, so that it is prevented from being cramped or bound in the groove d^3 .

While I have shown what I deem the preferable form of construction I wish it understood that other forms may be employed so long as the principle of the external gear is retained, which feature I regard as of much importance. I have shown but a three-stepped gear for convenience, but it will be evident that any desired number may be used, ranging from two to ten or twenty. The gear being supported directly on the axle is held positively irrespective of weight or number.

Having thus described my invention, what I claim as new, and desire to secure by Letters Patent, is—

1. In a gearing for crank-actuated machines, the combination with a crank-shaft and a sleeve, of an externally-toothed multo-gear loosely mounted on the shaft and comprising a series of gears of varying diameters, means for preventing an independent rotary movement of the gear, a vertically-adjustable power-transmitter ring having a toothed inner wall, an adjustable frame supporting the ring, a fixed support with which the frame slidingly engages, and shifting means for changing the relative position of the gear and sprocket, substantially as described.

2. In a changeable gear for crank-actuated machines, the combination with a shaft, of a stepped multo-gear sleeved directly on the shaft and formed with external teeth, means for preventing an independent rotation of the shaft and gear, a power-transmitting ring with which the gear engages, means for shifting the ring at substantially a right angle to the gear, and means for changing the relative lateral position between the gear and ring, substantially as described.

3. In a changeable gear for crank-actuated machines, the combination with a crank-shaft and its sleeve, of a longitudinally-movable

multo-gear sleeved on the shaft having external teeth, means for preventing independent rotation of the gear and shaft, a plate fixed on the sleeve, a curved carrying-frame 5 slidingly supported on the plate, arms on the frame, a power-transmitting ring arranged to engage with the gear, a loose connection between the ring and arms, a shifting cam mounted on the sleeve having a plurality of 10 cam-paths therein, a sliding connection between the cam and carrying-frame, and a sliding connection between the cams and gear, substantially as described.

4. In a changeable gear for crank-actuated machines, the combination with a crank-shaft and its sleeve, of an externally-toothed multo-gear on the shaft, a power-transmitting ring arranged to engage the gear, a curved carrying-frame for the ring comprising two side 15 bars, and laterally-extending supporting arms, a plate fixed to the sleeve and with which the frame slidingly engages, and a shifting device mounted on the sleeve inwardly beyond the plate for changing the relative position of the ring and gear, substantially as 20 described.

5. In a changeable gear for crank-actuated machines, the combination with a crank-shaft and its sleeve, of an externally-toothed multo-gear, slidingly supported on the shaft, means 25 for preventing independent rotation of the gear and shaft, a sprocket-ring independent of the gear, having internal teeth arranged to engage the gear, a carrying-frame located inwardly beyond the gear, arms extending outward from the frame and having a journal connection with the ring, a fixed support for the frame with which the latter has a sliding connection, and a shifting device having connections 30 with the frame and gear and loosely sleeved on the frame, substantially as described.

6. In a changeable gear for crank-actuated

machines, the combination with a crank-shaft and its sleeve, of a multo-gear on the shaft, 45 a power-transmitting ring arranged to engage the gear, means for adjustably supporting the ring directly on the sleeve, a rotatable shifting device having horizontal and vertical cam-grooves therein and connections engaging in the grooves for changing the relative positions of the gear and ring, substantially 50 as described.

7. In a changeable gear for crank-actuated machines, the combination with a shaft, of a multo-gear on the shaft, a sprocket-ring independent of the gear, a ring supporting the sprocket-ring loosely engaging therewith, a curved carrying-frame for the supporting ring located inward from the ring, arms connecting the carrying-frame and supporting ring, a fixed support for the carrying-frame a cam-plate having loose connection with the carrying-frame and gear, and comprising a horizontal plate and a vertical plate having 60 cams thereon, and a lever for shifting the plates, and means operated by the cams for shifting the gears and ring, substantially as described.

8. In a changeable gear for crank-actuated machines, the combination with a shaft, of an external toothed multo-gear loosely mounted to move longitudinally on the shaft, a power-transmitting ring arranged to be engaged with the gear and movable in a vertical plane only, and means for changing the relative position of the ring and gear, so that the ring will be caused to engage the different steps or sections of the gear, substantially 70 as described.

In testimony whereof I affix my signature in presence of two witnesses.
